FLOODLIGHT HOUSING OR SIMILAR ARTICLE

Lawrence M. Rheingold, Baldwin, N.Y., assignor to
Templet Industries, Inc., Brooklyn, N.Y., a corporation
of New York

Filed Apr. 2, 1962, Ser. No. 69,557

Term of patent 3½ years

(Cl. D48—20)

FIG. 1

FIG. 2

FIG. 3

FIG. 4

FIG. 5

FIG. 6

FIG. 1 is a front elevational view of a floodlight housing or similar article showing my new design;

FIG. 2 is a rear elevational view of the same;

FIG. 3 is a bottom view of the same;

FIG. 4 is a side elevational view of the same;

FIG. 5 is a rear perspective view of the same, looking in one direction; and

FIG. 6 is a view similar to that of FIG. 5, looking in an opposed direction.

The dominant features of my design reside in the portions shown in full lines.

I claim:

The ornamental design for a floodlight housing or similar article, substantially as shown and described.
